UNITED STATES PATENT OFFICE.

ARTHUR M. BARNHART, OF CHICAGO, ILLINOIS, ASSIGNOR TO HIMSELF
AND ALSON E. BARNHART, OF SAME PLACE.

DESIGN FOR A FONT OF TYPE.

SPECIFICATION forming part of Design No. 17,162, dated March 8, 1887.

Application filed February 7, 1887. Serial No. 226,841. Term of patent 7 years.

To all whom it may concern:

Be it known that I, ARTHUR M. BARNHART, a citizen of the United States, residing in the city of Chicago, county of Cook, and State of Illinois, have invented and produced a new and original Design for a Font of Printing-Types, of which the following is a specification, reference being had to the accompanying typographical illustration, forming a part 5 to hereof.

The general character of the design is Gothic, of light weight, and extended; and it consists of capitals, lower case, points, figures, \$, and character &. 15 The special features are the uniform weight of all lines, an arched top, as in lower-case m; a cross-line extending beyond the side of the letter to the right and ending in a sharp corner, with a ball on the upper side, as in A; 20 a cross-line not extending all the way across the letter and ending in a downward curve and a drop inside, as in B; a diagonal line starting at the extreme lower right-hand of the letter, bearing upward to the left, crossing 25 another line beginning at the upper right-hand

corner and ending in a short downward curve, and a ball near the vertical stem, as in K; a vertical line at the lower left-hand end of a loop, as in P; a line starting from the right-hand lower corner, passing upward to the left, 30 crossing the lower line of a loop and terminating in a short upward curve and a ball, as in R; two lines forming an acute angle, one of which starts from a point inside the bottom line of the letter, crosses the same obliquely, 35 forms a junction with a line running parallel to the bottom of the letter, as in Q.

I claim—

The design for a font of printing-types of Gothic character, with top and bottom lines of 40 uniform weight with the side lines, arched top, horizontal cross-line ending in ball, diagonal lines ending in curve and ball, loop ending in a vertical line, and acute angles forming the tail of letter, as described, and shown in the accompanying illustration. 45

ARTHUR M. BARNHART.
